US00D633526S

(12) United States Design Patent
Trabona et al.

(10) Patent No.: US D633,526 S
(45) Date of Patent: * Mar. 1, 2011

(54) ICON FOR A DISPLAY SCREEN

(75) Inventors: Denise Michele Trabona, Seattle, WA (US); Kieran M. Phelan, Seattle, WA (US); Colin Anthony, Bothell, WA (US); Lindsey Renee Barchek, Seattle, WA (US)

(73) Assignee: Microsoft Corporation, Redmond, WA (US)

() Term: 14 Years

(21) Appl. No.: 29/360,231

(22) Filed: Apr. 22, 2010

(51) LOC (9) Cl. 14-04

(52) U.S. Cl. D14/495

(58) Field of Classification Search D14/485-95; D18/24-33; D19/6, 52; D20/11; D21/324-33; 715/700-867, 973-77

See application file for complete search history.

(57) CLAIM

The ornamental design for an icon for a display screen, as shown and described.

DESCRIPTION

The FIGURE is a front view of an icon for a display screen showing the new design.

The broken line showing of the display screen is for environmental purposes only and forms no part of the claimed design.
